CLAIM

The ornamental design for a toy building block, as shown and described.

DESCRIPTION

FIG. 1 is a front view of a toy building block of the present invention;

FIG. 2 is a rear view thereof;

FIG. 3 is a top plan view thereof;

FIG. 4 is a bottom view thereof;

FIG. 5 is a right side view thereof;

FIG. 6 is a left side view thereof;

FIG. 7 is a perspective view thereof; and,

FIG. 8 is a cross-sectional view in the direction indicated by the arrows 8-8 of the toy building block of FIG. 1.

The broken lines are for the purpose of illustrating portions of the article that form no part of the claim.
